(57) **CLAIM**

The ornamental design for a grill light, as shown and described.

DESCRIPTION

FIG. 1 is a front perspective view of a grill light showing our new design.

FIG. 2 is a front plan view thereof.

FIG. 3 is a rear plan view thereof.

FIG. 4 is a top plan view thereof.

FIG. 5 is a bottom plan view thereof.

FIG. 6 is a right side elevational view thereof; and,

FIG. 7 is a left side elevational view thereof.

In the drawings, the broken line showing of a post and collar depicts environmental subject matter and forms no part of the claim.
